DESIGN FOR AN ARTIFICIAL FISH LURE

Joseph V. Ferriot, Akron, Ohio

Application April 21, 1948, Serial No. 145,882

Term of patent 14 years

(Cl. D31—4)

To all whom it may concern:

Be it known that I, Joseph V. Ferriot, a citizen of the United States and a resident of Akron, in the county of Summit and State of Ohio, have invented a new, original, and ornamental Design for Artificial Fish Lure, of which the following is a specification, reference being had to the accompanying drawings, forming part thereof.

In the drawings:

Figure 1 is an elevational view of an artificial fish lure, illustrating my new design, contrasting shading being utilized in the drawing to designate contrasting coloring of the lure.

Figure 2 is a side edge of the lure, as viewed at the top of Figure 1.

Figure 3 is a cross-section taken substantially on the line 3—3 of Figure 1.

The essential feature of my design resides in the portions shown in full lines in the drawing.

What I claim is:

The ornamental design for an artificial fish lure, substantially as shown and described.

JOSEPH V. FERRIOT.
